LIFE PRESERVER AND SWIMMING-AID
DEVICE

Elwell Eastman, Portland, Oreg.

Application December 26, 1942, Serial No. 470,203

1 Claim. (Cl. 9—17)

This invention relates to improvements in life-preservers and swimming aid devices, and has for its principal object the provision of a device of this character which is of simple, efficient, durable, and inexpensive construction and wherein the floats, or buoyant members thereof, are made entirely of plastic material in contrast to buoyant members heretofore made for this purpose out of cork, kapok, and the like.

A further object of the invention is the provision of a device of this character wherein the buoyant elements thereof are of such shape that they conform snugly and comfortably to the body of the wearer, and in such a manner that no crotch straps are needed.

The foregoing and other objects will be apparent as my invention is more fully herein-after described in the following specification, illustrated in the accompanying drawing, and finally pointed out in the appended claim.

In the drawing:

Figure 1 illustrates a life-preserver made in accordance with my invention and attached to the body of a wearer.

Figure 2 is a perspective view of the life-preserver is an open position.

Figure 3 is an enlarged sectional plan view of one of the buoyant elements taken on the line 3—3 of Figure 1.

Referring now more particularly to the drawing:

As illustrated in Figure 2, the invention comprises a plurality of hollow, buoyant floats indicated at 1, 2, 3, and 4, preferably four in number and diametrically opposed to each other, as shown in Figure 1. The device may be attached to the body of the wearer in such manner that there will be one buoyant member on each side, one in the front and one in the rear. Each float made of plastic material is of hollow construction having inner, outer, bottom and top walls. The outer wall is of convex formation and the

inner wall is concave to fit the contour of the body of the wearer. The top wall of each float is inclined downwardly and outwardly away from the inner wall, as at 5, to fit comfortably beneath the armpits of the wearer, or between the arms and body of the wearer. The floats are attached in spaced relation to each other by means of straps 6 and 7 secured, respectively, to the upper and lower extremities of the exterior surface of the inner wall of each float. The ends of the straps 6 and 7 may be secured together by any approved form of buckles or fastening elements, as at 8.

To the upper strap 6, I secure shoulder straps 9 and 10, each provided with any approved form of fastening elements such as buckles or the like, as indicated at 11 and 12.

Due to the light weight construction and snug and comfortable manner in which the device 20 clings to the body of the wearer it is readily adaptable for use as an aid in swimming or for swimming instructions as well as use as a life-preserver.

Having thus described my invention, what I 25 claim as new and desire to protect by Letters Patent is:

A life preserver comprising a plurality of hollow buoyant floats made of plastic material and each having a top wall, bottom wall, a concave inner wall, and a convex outer wall, said top wall being inclined downwardly and outwardly away from the inner wall, said floats being attached to each other in spaced relation by straps secured to the upper and lower extremities of the exterior surface of the inner wall of each float and terminating in adjustable fastening elements for attaching the floats to the body of the wearer, and shoulder straps secured to said upper strap for positioning the floats on the body of 40 the wearer.

ELWELL EASTMAN.
